UNITED STATES PATENT OFFICE.

WILSON S. GILLELAND, OF NEWKIRK, OKLAHOMA TERRITORY,
ASSIGNOR OF NINE-SIXTEENTHS TO E. M. MARKEL, OF DES
MOINES, IOWA.

GRAIN-DOOR.

No. 828,943.

Specification of Letters Patent.

Patented June 19, 1906.

Application filed November 17, 1905. Serial No. 287,804.

To all whom it may concern:

Be it known that I, WILSON S. GILLELAND, a citizen of the United States, and a resident of Newkirk, in the county of Kay and Territory of Oklahoma, have made certain new and useful Improvements in Grain-Doors, of which the following is a specification.

My invention is an improvement in grain-doors; and it consists in certain novel constructions and combinations of parts herein-after described and claimed.

In the drawings forming a part hereof, Figure 1 is a side elevation of a part of a car provided with my improved grain-door, a portion of the door being broken away to show the door upon the opposite side of the car. Fig. 2 is a section on the line 2 2 of Fig. 1, and Fig. 3 is a section on the line 3 3 of the same figure.

20 The car A illustrated is of the box type and is provided with a door-opening a in the side thereof, the floor of the car being provided with a sill a², extending between the posts a', forming the sides of the openings.

25 Leaves B are connected by means of hinges b with plates b', secured to the inner faces of the posts by means of lag-screws b² or any other suitable means. By referring to Figs. 1 and 2 it will be seen that the hinges b are arranged in such manner that the leaves open inward with respect to the car and the plate b' is spaced from the edge of the posts, thus allowing the leaves to abut against the posts when in alinement with the plate. This arrangement relieves the strain upon the hinges 30 during the outward motion of the door proper.

35 Doors CC', provided with fan-shaped openings c', are hinged to the leaves by means of the hinges c, the hinges being arranged in 40 such manner that the doors will open outward with respect to the car or in an opposite direction to the opening of the leaf. One of the doors, C in the present instance, is provided with a plate c², arranged upon the inner 45 face and projecting beyond the edge thereof to receive the door C' for preventing inward movement of the latter door with respect to the former.

Plates D, substantially triangular in outline, 50 are provided for closing the opening c', the plates being pivoted to the doors by a pivot-pin d. The plates are provided with handles d' for convenience in manipulating the same

and when closed rest upon a pin d², the outward motion of the plates with respect to the 55 doors being restrained by means of keepers d², secured to the doors and projecting over the free ends of the plates.

Plates E, of a length equal to the width of the door, are connected to the inner face of 60 each of the doors, near the lower edge thereof, by means of hinges e, the plates when closed engaging the inner edge of the sill a² and closing the opening between the bottom of the door and the sill. 65

A means H for fastening the doors is provided comprising catches h, secured to one of the doors, C in the present instance, and engaged by the outwardly-projecting flanges h⁴, upon one of the arms of the rocking lever h', 70 pivoted to the door C by means of the pin c². The catches h are of the shape shown in Fig. 2, comprising a portion h⁸ for attachment to the door and a hook portion h⁹ for engaging the flanges. 75

The rocking levers h' are three in number in the present instance, and the outer arms of each of them are connected together by a bar h⁵ pivoted thereto. A handle h², integral with the outer arm of the uppermost rocking lever, 80 is provided for manipulating the bar, a pin h³, connected to the handle by means of a chain h⁶, being provided for securing the handle when the doors are fastened, the pin traversing alined openings in the handle and the door. A lug h⁷, integral with the lowermost rocking lever, is provided for engaging a groove a³ in the door-sill when the doors are fastened. The engagement of the lug with the groove prevents movement of the doors 85 with respect to the sill. 90

When the car is to be loaded, the doors are closed and are secured by manipulating the handle h² to engage the rocking levers with the catches. The same movement engages 95 the lug with the groove, thus securing the doors in their closed position. The plates E of their own weight rest against the door-sill, closing the crack between the door and the sill. When a car is to be unloaded, the fastening device is released and the doors are permitted to swing outwardly on their connection with the leaves. When the car is not in use, the doors may be swung inwardly against the inside of the car on the hinges b. 100 105

Having thus described my invention, what

I claim as new, and desire to secure by Letters Patent, is—

The combination with the car having a door-opening provided with a sill, of doors hinged to the sides of the opening, a plurality of catches on one of the doors, a plurality of rock-levers pivoted to the other door, said levers having their outer ends provided with flanges for engaging the catches, the inner 10 end of one of said levers being extended to form a handle, and a bar connecting the inner

ends of said levers whereby to constrain them to move in unison, and one of said levers being provided with an integral lug for directly engaging the sill when the flanges are engaged 15 with the catches, whereby to prevent movement of the doors with respect to the sill.

WILSON S. GILLELAND.
